UNITED STATES PATENT OFFICE.

HARRY E. DE VAUGHN, OF MORGANTOWN, WEST VIRGINIA, ASSIGNOR TO WALTER A. JONES, OF MORGANTOWN, WEST VIRGINIA.

FLATTENING-OVEN.

1,308,341.

Specification of Letters Patent.

Patented July 1, 1919.

Application filed October 6, 1916. Serial No. 124,093.

To all whom it may concern:

Be it known that I, HARRY E. DE VAUGHN, a citizen of the United States, residing at Morgantown, in the county of Monongalia 5 and State of West Virginia, have invented new and useful Improvements in Flattening-Ovens, of which the following is a specification.

This invention is an improvement in 10 ovens of the type commonly employed to flatten window glass.

In the flattening apparatus now in general use, the flattening wheel is usually supported upon a pedestal with all of the 15 drive and rotating mechanism set in a deep cellar, and as a consequence, when repairs of any kind are necessary, as is often the case, the operator must stop work and cool the oven off so that workmen may go into 20 the cellar, under the wheel, in order to gain access to the parts to be repaired. Thus, repairs are not only difficult by reason of the inaccessibility of the parts, but each 25 time that repairs are necessary a financial loss is entailed by reason of the shutting down of the apparatus.

One of the objects of the present invention is to overcome the foregoing objectionable features by providing a flattening 30 oven with a wheel having all of its driving mechanism outside of the oven, and above the same, away from the heat, and easy of access for the purpose of making repairs whenever found necessary. A further object 35 is to provide a flattening oven having a wheel suspended from a suitable support, located at a point where the temperature of the oven can have no effect detrimental to the perfect and efficient operation of 40 the parts at all times. A further object is to provide a flattening oven having a suspended wheel, and means whereby the said wheel may be operated either by mechanical power or manually, as may be 45 desired or necessary. A further object is to provide a flattening oven having a suspended wheel so supported that it may be raised or lowered in the oven, to regulate the clearance between the face of the flattening stone and the clay mantel or dividing 50 walls in the oven, without changing the relation of the master gear wheel to the driving pinion. A further object is to provide a flattening oven having a suspended 55 wheel, and means for positively adjust-

ing the wheel to regulate its vertical and horizontal elevation in the oven, without necessitating the cooling off of the oven or interfering with the operation thereof. A further object is to provide a flattening oven 60 so constructed that deep and expensive cellars are rendered unnecessary. A further object is to provide a flattening oven having its mantel walls and cap suspended from an external support. 65

The invention will be hereinafter fully set forth and particularly pointed out in the claims.

In the accompanying drawings:—

Figure 1 is a transverse sectional view 70 of a flattening oven, illustrating the invention. Fig. 2 is a plan view of the flattening oven, the mantel walls being shown in dotted lines and in section. Fig. 3 is a top plan view illustrating the driving mechanism for the wheel. Fig. 4 is a sectional view illustrating a slight modification.

Referring to the drawing, 10 designates a flattening oven, which may be of any preferred construction, the same being provided with the shovel pan track 11, burners 12, and the mantle walls 13, dividing the oven into the heating chamber and flattening compartment 14, annealing chambers 15 and 16, and piling compartment 17. Extending through the compartment 16 are the 80 lever rods 18.

Resting upon the furnace walls, is a supporting frame formed of beams 19, connected by suitable cross pieces 20, and secured to said frame are the beams 21, which sustain the weight of the flattening wheel 22. Said wheel is keyed, or otherwise secured to the shaft 23, the lower end of which is rotatably mounted in a bearing 90 sleeve 24, preferably provided with anti-friction bearings 25, said sleeve being maintained in a central position by means of guy rods 26, attached to the sleeve and extending through the wall of the oven, being 95 provided with means, illustrated at 27, whereby the tension upon said guy rods may be adjusted. The upper end of the shaft 23, is passed through and splined to a master gear wheel 28, the hub of which rests upon bearings 29, supported by a platform, resting upon the suspension beams 21. The upper extremity of the shaft 23 is threaded to receive a nut 31, which forms a stop for an abutment collar 32, a spring 100 105

33, interposed between the master gear wheel 28 and said abutment collar 33, serving to resiliently support the weight of the flattening wheel 22 and its shaft 23. By 5 means of the nut 31, the wheel 22 may be adjusted to the proper level within the oven to increase or decrease the clearance between the flattening stones 34 and the mantel walls 13.

10 Meshing with the master gear wheel 28, is a pinion 35, secured to a drive shaft 36, connected up in suitable manner with a motor 37, of any preferred type, an electric motor being conventionally shown. Also 15 meshing with the master drive pinion 28, is a pinion 38, carried by a shaft 39, connected in suitable manner, as by sprocket gearing 40, with a hand crank 41, positioned for convenient access. By means of 20 this arrangement, should the motor 37 become disabled, the shaft and flattening wheel may be manually operated from the crank 41. In order to arrest rotation of the flattening wheel at any time a suitable 25 brake may be provided. For purposes of illustration, the brake is shown as comprising a band 42, encircling the periphery of the master gear wheel 28, and connected to an arm 43, operated by a magnet 44.

30 In those installations where very large and heavy flattening wheels are employed, it is preferable to employ the construction illustrated in Fig. 4, in lieu of the bearing sleeve 24. In this form, the underside of 35 the wheel is provided with a track 45, positioned to travel upon tapered rollers 46, mounted in anti-friction bearings, the supporting frames 47, for said rollers being adjustable to maintain engagement with the 40 track, by means of adjusting rods 48, having their outer ends connected with adjusting members 49, outside of the oven wall.

The mantel walls and cap of the flattening oven may be supported in any suitable 45 manner. It is preferred, however, to provide the blocks forming the mantel walls, with recesses 50, to receive supporting members 51, attached to suspension rods 52, extending upwardly through the cap of the 50 oven, and secured to the cross pieces 20 of the supporting frame. In this manner the mantel walls 13 and the oven cap 53 are suspended from said supporting frame.

To protect the shaft 23, from the intense 55 heat of the oven, the same is surrounded by a heat insulating jacket 54, suspended by means of rods 55, attached to the suspending frame, an air space 56 being provided between said jacket or sleeve 54, and the shaft.

60 From the foregoing it will be readily understood that a flattening oven is provided in which the flattening wheel is suspended from a point above and outside of the oven, and that all of the bearings and 65 driving mechanism are so positioned that

they are readily accessible, and at the same time they are located at points where the intense heat of the oven can have no detrimental effect upon their perfect and efficient operation. It will be further noted 70 that deep and expensive cellars are rendered unnecessary, and that repairs may be made at any time without dismantling the apparatus. A further advantage is obtained by means of the adjustment, whereby the vertical and horizontal elevation of the flattening wheel within the oven may be conveniently regulated. By providing the manual operating means for the master gear wheel, as well as the mechanical motor for actuating said gear wheel, simple means are provided whereby operation of the oven will 75 not have to be discontinued should the motor become deranged. 80

Having thus explained the nature of the 85 invention, and described an operative manner of constructing and using the same, although without attempting to set forth all of the forms in which it may be made, or all of the forms of its use, the following is 90 claimed:—

1. A flattening oven for glass ware comprising a suspension frame, a vertically disposed rotatable shaft extended through said suspension frame, a driving member rotatably supported upon said suspension frame, means whereby said shaft is yieldably suspended from said driving member, and a flattening wheel attached to the lower end of 95 said shaft. 100

2. A glass flattening oven comprising a suspension frame, a vertically disposed rotatable shaft extended through said suspension frame, a driving member rotatably supported upon said suspension frame and having a slidably engagement with said shaft, means whereby said shaft is yieldingly suspended from said driving member, and a flattening wheel attached to the lower end of 105 said shaft. 110

3. A glass flattening oven comprising a suspension frame, a vertically disposed rotatable shaft extended through said suspension frame and provided at its upper end with an abutment, a driving member rotatably supported by said suspension frame, a spring interposed between said driving member and said abutment whereby said shaft is yieldingly suspended from said driving member, and a flattening wheel attached to the lower end of 115 said shaft. 120

4. An improvement in flattening ovens comprising a vertically disposed rotatable shaft, means connected with the upper end of the shaft for suspending the same, means 125 for steadyng the lower end of the shaft, a flattening wheel attached to said shaft near its lower end, and means for adjusting said steadyng means radially, with respect to said wheel. 130

5. An improvement in flattening ovens comprising a vertically disposed rotatable shaft, means connected with the upper end of the shaft for supporting the same, means 5 for steadyng the lower end of the shaft, a flattening wheel attached to said shaft, rods attached to said steadyng means, and means for adjusting said rods to shift said steadyng means.
- 10 6. A glass flattening oven comprising a suspension frame, a vertically disposed rotatable shaft extended through said suspension frame, a driving member rotatably supported upon said suspension frame, means whereby said shaft is suspended from said driving member, a flattening wheel attached to the lower end of said shaft, and adjustable means for steadyng the lower end of said shaft.
- 15 7. A glass flattening oven comprising a suspension frame, a vertically disposed rotatable shaft extended through said suspension frame, a driving member rotatably supported upon said suspension frame, means whereby said shaft is suspended from said driving member, a flattening wheel attached to the lower end of said shaft, and adjustable guy rods connected with the lower end of said shaft to steady the same.
- 20 8. A glass flattening oven comprising a supporting frame, a suspension frame sustained thereby, a shaft rotatably suspended at its upper end from said suspension frame, a flattening oven attached to the lower end 25 of said shaft, mantel walls suspended from said supporting frame, and an oven cap sustained by said suspending mantel walls.
- 30 9. A glass flattening oven comprising a supporting frame, a suspension frame sustained thereby, a rotatable driving member sustained by said suspension frame, a shaft rotatably suspended at its upper end from said driving member, a flattening wheel attached to the lower end of said shaft, rods 35 suspended from said supporting frame, mantel walls sustained by said suspended rods, and an oven cap sustained by said suspended mantel walls.
- 40 10. A glass flattening oven comprising a supporting frame, mantel walls formed of horizontally alined blocks, suspension rods 45 depending from said frame and sustaining said blocks in suspension, said supporting frame and said suspension rods constituting the sole supporting means for said blocks, 55 and an oven cap sustained by said suspended mantel walls.
- 50 11. A glass flattening oven comprising a supporting frame, mantel walls formed of horizontally alined blocks, suspension rods 60 depending from said frame and sustaining said blocks in suspension, said supporting frame and said suspension rods constituting the sole supporting means for said blocks, 65 and an oven cap located below said frame and sustained by said suspended mantel walls, said rods being passed through said cap.
- 65 12. A glass flattening oven comprising a supporting frame, mantel walls formed of 70 horizontally alined blocks having recesses in their undersides, supporting members within said recesses, suspension rods depending from said frame and engaging said supporting members to sustain said blocks in suspension, and an oven cap sustained by said suspended mantel walls. 75
- 70 13. A glass flattening oven comprising a supporting frame, mantel walls formed of horizontally alined blocks, means for suspending said blocks from said frame, said frame and said suspending means constituting the sole support for said blocks, and an oven cap sustained by said suspended mantel walls. 80
- 75 14. A glass flattening oven comprising a supporting frame, a vertically disposed shaft rotatably suspended from said frame and having a flattening wheel attached thereto, a protecting device for said shaft suspended from said frame and supported wholly by the latter, mantel walls suspended from said frame, and an oven cap sustained by said suspended mantel walls. 90
- 80 In testimony whereof I have hereunto 95 set my hand in the presence of two subscribing witnesses.
